UNITED STATES PATENT OFFICE.

ADOLPH W. SCHWARZ, OF ST. PAUL, MINNESOTA.

TOY.

Application filed August 10, 1922. Serial No. 580,875.

To all whom it may concern:

Be it known that I, ADOLPH W. SCHWARZ, a citizen of the United States, residing at St. Paul, in the county of Ramsey and State of Minnesota, have invented certain new and useful Improvements in Toys, of which the following is a specification.

This invention relates to toys designed for use in connection with flying kites, and has 10 for its principal object to provide improved means, to be used in connection with the kite line, for automatically detaching an object which is caused to traverse, and is operatively connected to the line, during a kite 15 flying operation, to thereby afford amusement for children when said object is a toy, or for conveying messages and the like.

A further object of the invention is to provide improved means for guiding an object 20 in connection with the line in its travel over the latter in the direction of the kite.

Other objects of the invention will be pointed out as this specification progresses, the invention consisting in the construction, 25 combination and arrangement of parts hereinafter described and claimed.

In the accompanying drawings, forming part of this specification,

Figure 1 is a perspective view of a preferred form of my invention, showing it applied to a kite line.

Figure 2 is a longitudinal sectional view of my improved detaching device.

Figure 3 is a front elevation of my improved conveyor for traversing the line.

Figure 4 represents a modified form of a part of the detaching device and

Figure 5 is a perspective view of the released object.

In the drawings, 1 designates a string or line, to which is attached the kite 2, which latter may be of any conventional form, the kite being here shown held suspended by the wind blowing in the direction indicated 45 by the arrow.

Adapted to roll on the line, is the sheave or roller 3, formed with an appreciably deep peripheral groove 4. The roller has a central bore 5, wherein is loosely journaled the 50 depending connecting member or hook 6, to the outer extremity of which is suitably connected the wind propelled device 7. The device here shown constitutes a parachute for which latter the hook and its roller 55 function as ballast in its flight, said parachute consisting of a wind catching or sail

member 8, and flexible tie members 9 of uniform length attached at intervals to the border of the sail member, and collectively to the connecting hook member. The connecting member, which is rotatable in the plane of the roller extends beyond the peripheral flanges thereof, and is preferably crimped to form oppositely disposed knees as at 10, which knees loosely receive the 60 roller between them and tangentially engage with the sides thereof to effect a minimum amount of friction, and thereby facilitate its free movement. The eye 11, forming the terminal of the connecting member or hook 6, is preferably located centrally of the groove 4. Preferably connected into the line, is the wire support 12, formed at its ends with loops 13 and 13' respectively, the support, as here shown, thus forming a part 70 of the line. Surrounding the support is the conic shell or hollow cone 14, formed with an outwardly flaring rim 14'. The apex of the cone is formed with a small opening 15 through which the wire support 12 loosely extends, the cone being held against removal from the latter by the return wires 13'' which form parts of the loops 13 and 13'. The wire is connected into the line in a manner to bring the flaring rim at the base 80 of the cone nearest the kite, and enable the cone to rest longitudinally with the inner side of its surrounding wall, on said wire as to be swingable laterally thereon.

In operation, the cone is placed a suitable distance from the kite to prevent the released object from colliding therewith. From five to seven feet has proved to be a suitable distance. The kite having reached the desired height, the roller carrying the 95 parachute is placed in the line, when the sail member 8 will catch the wind and the device will rapidly traverse the line until it engages with the cone. As the roller traverses the cone, the depending member 6 will impinge on the side of the cone and thereby cause it to swing laterally, owing to the tautness of the tie members 9, due to the pull of the sail member.

As indicated in dotted lines, in Figure 3, 105 (wherein the circles 16—17—18 and 19 designate respectively the sectional contours of the cone at the corresponding numbers in Figure 2) the cone is gradually swung side-wise concurrently with the travel of the roller thereon, thereby gradually moving the line 1 which forms the sole support for 110

the roller from the point 20 symmetrically directly under the latter, to the point 21 located an appreciable distance outside thereof, thus causing the roller to fall by gravity 5 from the side of the cone. The parachute will obviously assume upright position as shown in Figure 5.

It is to be understood, that the wire 12 may be dispensed with, and the cone supported directly by the line, in which case a knot in the line, as at *a*, Figure 4, will hold 10 the cone positioned. Further, other wind propelled objects may be substituted for the parachute.

15 The rim 14' functions as a stop and to further deflect the falling roller as it leaves the cone, to steer it away from the kite, while the cone proper functions as a switch element to guide the roller off the line. The 20 forced change of position of the center of gravity of the cone by the advancing member 6, (Figure 3) causes the weight of the cone to push said member outwardly, thus assisting in switching the roller off the line. 25 The cone virtually is a continuation of the line from its apex to the rim, and corresponds to a section of line which gradually increases in diameter from the apex, where it is small enough to enter the groove of the 30 roller, to the rim, where it is several times larger than the width of the groove, so that the roller travels approximately with the periphery of its flanges along a line *b* as shown in Figure 4. The hook member 6 and 35 the roller together constitute a hook, the groove of the roller functioning as the jaw of the hook, which jaw may be termed a rotary jaw.

I claim:

1. In a device of the class described, the combination with the line of a flying kite, of a wind propelled device, a hook formed with an elongated shank attached to said device and adapted to hook over said line so that the shank will depend therefrom and travel 40 thereon toward the kite when propelled by said wind propelled device, a hollow cone carried by the line in the path of travel of said hook, the apex thereof directed toward the latter and being of a size to enter the 45 jaw of the hook, but the base of the cone being larger than said jaw, said cone being constructed to enable the line to be extended loosely through the hollow thereof and to engage with said shank to be swung laterally 50 thereby during travel thereof.

2. In a device of the class described, the combination with a kite line, of a wind propelled device, a hook formed with an elongated shank attached to said device and 60 adapted to hook loosely over the line to travel thereon when said wind propelled device is propelled, a hollow cone having a wire support extending axially longitudinally through the hollow thereof to enable the 65 cone to rotate and swing laterally thereon, the apex of the cone being directed toward said hook and being of a size to enter the jaw of the said hook, but the cone being larger than said jaw at the base thereof, and an eye in each end of said wire support 70 for attaching the guide line and locking said cone against removal therefrom.

In testimony whereof I affix my signature.

ADOLPH W. SCHWARZ.
